(57) **CLAIM**

I claim the ornamental design for a transfer tray, as shown and described.

DESCRIPTION

FIG. 1 is a top perspective view of a transfer tray showing my new design;

FIG. 2 is a top plan view thereof;

FIG. 3 is a bottom plan view thereof;

FIG. 4 is a first side elevation view thereof; and,

FIG. 5 is a second side elevation view thereof.

The broken line portion of the figure drawings is included to show unclaimed subject matter only and forms no part of the claimed design.
